Attorney.

UNITED STATES PATENT OFFICE.

JOSEPH X. MATHIEU, OF PITTSFIELD, MASSACHUSETTS, ASSIGNOR TO GENERAL ELECTRIC COMPANY, A CORPORATION OF NEW YORK.

MOTOR CONTROLLER.

1,410,944.

Specification of Letters Patent. Patented Mar. 28, 1922.

Application filed September 2, 1921. Serial No. 497,869.

To all whom it may concern:

Be it known that I, JOSEPH X. MATHIEU, a citizen of the United States, residing at Pittsfield, county of Berkshire, State of Massachusetts, have invented certain new and useful Improvements in Motor Controllers, of which the following is a specification.

My invention relates to starting devices for electric motors, and in particular to a motor controller which is automatically returned to the off position in response to the occurrence of an abnormal condition in the motor circuit, such for instance as the failure of voltage or an overload. The invention has a particular application to starting compensators in which a switch member is biased to the off position and is operable in one direction from the off position to a starting position and in the other direction from the off position to a running position. Latching arrangements have heretofore been provided for insuring that the switch member will be required to be thrown to the starting position before being thrown to the running position, and latching arrangements have also been provided for maintaining the switch member in the running position against its bias to the off position. Arrangements have also heretofore been provided for releasing the switch member to return from the running position to the off position when an abnormal condition exists in the motor circuit.

One of the objects of the present invention is to provide an improved arrangement having the features of insuring that the switch member of the starting compensator will be required to be thrown to the starting position before being thrown to the running position, holding the switch member positively in the running position against its bias to the off position and releasing latching arrangement which holds the switch member in the running position with a hammer blow when abnormal conditions occur in the motor circuit. Another object of the invention is to provide an improved arrangement which is simple in construction, cheap to manufacture, and nevertheless reliable and effective in operation.

For a better understanding of the invention, reference is had to the accompanying

drawing, wherein the switch member 10 is biased to the off position shown by means of the spring 11. This switch member is mounted upon a rotatable shaft 12 which carries a set of movable contacts (not shown) adapted to engage a corresponding set of starting contacts on the left, only one of which, 13, is indicated. The set of movable contacts (not shown) is also adapted to make engagement with another set of running contacts, only one of which, 14, is indicated. The spring 11 cooperates with the two members 15 and 16 to bias the switch member 10 to the off position. These two members 15 and 16 are each mounted for a limited rotation with respect to the shaft 12 and their ends are connected together by the spring 11. When the switch member is in the off position, the two members 15 and 16 are in engagement with a stop 17, and a pin 18 on an extension of the switch member 10 is adapted to make engagement with either one of the members 15 and 16, depending upon the direction in which the switch member is thrown.

A pivoted latch 19 is provided for insuring that the switch member 10 will be required to be thrown to the starting position before being thrown to the running position, and the latch also has means for positively holding the switch member in the running position.

The electromagnet 20 has a winding which is adapted to be energized responsively to conditions in the motor circuit for controlling the latch 19. This electromagnet is provided with a magnetic movable member or armature 21, and the armature 21 is connected to the latch 19 by the link 22 which provides a lost motion connection between the armature and the latch. The link 22 is pivotally connected at one end of the latch and is provided with a slot at its other end within which a pin 23 carried by the armature 21 is adapted to move back and forth so as to place the latch under the control of the electromagnet to thereby effect the return of the switch member from the running position to the off position in response to abnormal conditions in the motor circuit. The connection of the winding of the electromagnet 20 in the motor circuit is not shown, since it is believed that the manner in which this con-

nection may be established in order to protect the controlled motor from no voltage conditions will be apparent to those skilled in the art. It will also be obvious to those skilled in the art that in case the motor is to be protected from overload conditions, some means must be provided for deenergizing the electromagnet in response to the overload conditions.

10 As thus constructed and arranged and with the parts in the various positions shown in the drawing, the operation of my invention is as follows:—In order to establish the starting connections, the switch member 10 will be thrown to the starting position by any suitable means, as for example, a handle (not shown) secured to the shaft 12. It will be observed that the latch 19 will permit this operation in case the switch member is thrown quickly, but that the operation will be arrested by the projection 24 in case it is attempted to throw the switch member slowly. The projection 25 will prevent the switch member from being thrown directly from the off position to the running position, but with the switch member in the starting position, the running position may be reached in case the switch member is thrown quickly. Thus a quick movement of the switch member will cause the latch 19 to be raised so that the projection 25 can be cleared.

The winding of the electromagnet 20 will be energized in the running position preparatory to protecting the controlled motor against abnormal circuit conditions. It will be observed that the movement of the latch 19 when the switch member is thrown from the off position to the starting position or from the starting position to the running position does not cause any movement of the armature 21 because of the fact that the armature is connected to the link 22 by the described pin and slot connection. It will also be observed that the movement of the armature 21 to the attracted position when the winding of the electromagnet is energized does not cause a movement of the latch. With the switch member in the running position and the latch 19 in engagement therewith so as to prevent the return thereof to the off position by reason of the bias of the spring 11, in case some abnormal circuit condition arises and the winding of electromagnet 20 is deenergized, the armature 21 will be permitted to drop in accordance with the gravity bias, the pin 23 will strike the link 22 a hammer blow and the hammer blow will be imparted to the latch 19, so that the latch is quickly raised. The switch member is thus permitted to return quickly to the off position and the parts assume their respective positions shown in the drawing.

65 In accordance with the provisions of the

patent statutes, I have described the principle of operation of my invention together with the apparatus which I now consider to represent the best embodiment thereof, but I desire to have it understood that the apparatus shown is only illustrative and that the invention may be carried out by other means.

What I claim as new and desire to secure by Letters Patent of the United States, 75 is,—

1. In a motor controller, a switch member biased to an off position and movable against its bias in one direction to a starting position and against its bias in the opposite direction to a running position, a latch co-operating therewith for holding the said member in the running position and for compelling the said member to be thrown to the starting position before being thrown to the running position, an electromagnet energized responsively to conditions in the motor circuit for releasing the said latch, the said electromagnet having a magnetic movable member magnetically held in one position against its bias to a second position, and a connection between the said latch and magnetic member through which a hammer blow is imparted to release the holding effect of the said latch in response to the operation of the said magnetic member to its biased position.

2. In a motor controller, a switch member biased to an off position and movable against its bias in one direction to a starting position and against its bias in another direction to a running position, a pivoted latch co-operating therewith for holding the said member in the running position and for compelling the said member to be thrown to the starting position before being thrown to the running position, an electromagnet energized responsively to conditions in the motor circuit for releasing the said latch, the said electromagnet having a magnetic movable member magnetically held in one position against the bias of gravity to the second position, and a pin and slot connection between the said latch and magnetic member through which a hammer blow is imparted to release the holding effect of the said latch in response to the operation of the said magnetic member to its biased position.

3. In a motor controller, a switch member biased to an off position and movable against its bias in one direction to a starting position and against its bias in another direction to a running position, a pivoted latch co-operating therewith for holding the said member in the running position and for compelling the said member to be thrown to the starting position before being thrown to the running position, an electromagnet energized responsively to 130

conditions in the motor circuit for releasing the said latch, the said electromagnet having a magnetic movable member magnetically held in one position against the bias of gravity to the second position, and a link providing a lost motion connection between the said magnetic member and latch through

which a hammer blow is imparted to release the holding effect of the said latch in response to the operation of the said magnetic member to its biased position. 10

In witness whereof, I have hereunto set my hand this 31st day of August, 1921.

JOSEPH X. MATHIEU.
